BUFFING WHEEL

Elisha Winthrop Hall, Scituate, Mass.

Application August 9, 1935, Serial No. 35,499

13 Claims. (Cl. 51—193)

This invention relates to improvements in buffing wheels which comprises a plurality of contacting layers of buffing material, such as cloth, or other fibrous material, and one of the objects 5 of the invention is to provide a buffing wheel in which the fraying of the buffing material will be effectively avoided.

In usual buffing wheel constructions the plurality of layers of fabric, or other buffing material, are united by lines of through and through stitching which in some instances are arranged concentrically, and others spirally, and others in parallelism in various designs and in intersecting lines or rows. In all such constructions the 10 wearing down of the buffing wheel exposes the section of the thread which extends through the buffing wheel and frequently a portion of the thread uniting the layers is broken in such manner that the released portion is projected out by 15 centrifugal force and whips around during the rotation of the buffing wheel in such a manner as to produce abrasions or scratches upon the surface being buffed.

By the present invention the adjacent layers 20 of the buffing material are united by a suitable tenacious adhesive at predetermined intervals and when the buffing wheel is worn down to the point or lines of adhesion the adhesive material is merely worn away without producing any such 25 frayed ends as result from the wearing away of the stitching thread as above described.

In usual buffing wheels in which the layers of buffing material are secured together by lines of through and through stitching the wearing away 30 of a through and through stitch releases all of the layers outside of the next inner through and through stitch.

Another object of the invention is to provide means which will adhesively unite successive adjacent layers in an offset or staggered arrangement out of registry with each other, thereby avoiding the release of the layers throughout any substantial segment of the buffing wheel, thus 35 insuring more uniformity of action of the buffing 40 wheel.

A further object of the invention is to provide a buffing wheel of the character specified in which the adjacent layers are united by intersecting narrow lines of tenacious adhesive so distributed 45 over the working area thereof as to form circular series of pockets, to retain the polishing or abrading material, which will successively open to the periphery of the wheel as it wears away.

A further object of the invention is to provide 50 a buffing wheel in which the adjacent layers are

united by intersecting series of preferably parallel lines of stitching so distributed over the working area as to form pockets successively opening to the periphery of the wheel as it wears away and in which the respective intersecting lines of adhesive uniting two adjacent layers are so positioned relatively to the series of intersecting lines of adhesive uniting the next adjacent layer that the pockets between successive adjacent layers are in whole or in part in non-registering or staggered relation relatively to each other, so that the polishing or abrading material contained in the pockets will be more uniformly presented to the work and a greater uniformity of abrading or 5 polishing action obtained.

These and other objects and features of the invention will more fully appear from the following description and the accompanying drawing and will be particularly pointed out in the 10 claims.

Illustrative embodiments of the invention are 15 shown in the accompanying drawing, in which,

Fig. 1 is an elevation of a buffing wheel in which the adjacent layers of buffing material are secured together by intersecting series of parallel 20 narrow lines of adhesive, the relative positions of the lines of adhesive of one pair of adjacent layers being in angular relation to the lines of adhesive uniting the next adjacent layer to the pair thus united;

Fig. 2 is an illustration of a buffing wheel showing the adjacent layers united by parallel sinuous 25 lines of adhesive;

Fig. 3 is a view showing adjacent layers of buffing material united by curved lines of adhesive 30 diverging from each other from the central portion of the wheel to the periphery thereof; and,

Fig. 4 is a view showing a buffing wheel in which adjacent layers of buffing material are united by suitably spaced radial narrow lines of adhesive, the lines of adhesive uniting adjacent 35 layers being offset from the lines of adhesive uniting the next layer thereto.

The buffing wheel embodying the present invention comprises broadly a plurality of contacting layers of fibrous buffing material firmly 45 united at predetermined spaced intervals by a tenacious adhesive, such as latex, a latex composition, glue, or other suitable adhesive material. The adhesive, particularly if animal glue, 50 may have combined with it a heat-resisting composition, such for example as zinc oxide in such proportion as will produce the desired result. It is found by experiment that approximately ten 55

per cent of zinc oxide is satisfactory for this purpose.

The adhesive may be so distributed as to unite adjacent layers of buffing material in any desired manner. In a preferred construction illustrated in Fig. 1 the outer layer 1 of buffing material, such as cloth, is united to the next adjacent layer 2 by a series of parallel narrow lines of adhesive 3, and also by an intersecting series of parallel narrow lines 4 of adhesive. In this construction the respect series of parallel lines of adhesive are arranged at right angles to each other, but of course may be positioned in any desired angular relation to each other. The next adjacent layer 5 of buffing material is united to the layer 2 by similar series of parallel lines of adhesive 6 and 7 in which the series of parallel lines of adhesive are disposed in angular relation to the other.

By reason of this construction a series of peripheral pockets 8 to receive and contain the polishing or abrading material are provided between the layers 1 and 2, and another series of peripheral pockets 9 are provided between the layers 2 and 5, the pockets 8 and 9 being arranged in offset or staggered relation to each other. Any number of adjacent layers of buffing material may be similarly united by intersecting parallel narrow lines of adhesive to provide a buffing wheel of the desired thickness.

By reason of this construction the wearing away of the wheels will progressively wear away the narrow lines of adhesive at the periphery, but inasmuch as the pockets 8 and 9 are in staggered relation to each other no substantial segments of any of the layers of the buffing material will be released from the adjacent layer, so that the action of the buffing wheel will be uniform.

In the construction illustrated in Fig. 1 a series of open pockets at the periphery of the wheel surround closed pockets 10 and 11 which are successively opened to the periphery as the wheel wears away. These closed pockets when opened by the wearing away of the wheel receive the polishing or abrading material so that uniform polishing or abrading action will continue until the wheel is worn down to such diameter that it is no longer efficient.

Where layers of cloth are employed as buffing material the layers are so arranged that the warp 50 and woof 12 of one layer is disposed in angular relation to the warp and woof 13 of the next adjacent layer, thereby avoiding soft spots in the periphery of the wheel which will occur if the warp and woof of adjacent layers are respectively 55 in parallelism.

A modified form of buffing wheel is illustrated in Fig. 2 in which the adjacent layers of buffing material are united by non-intersecting sinuous parallel rows of adhesive 14 having curved end portions 15 extending in similar angular relation to radii from their points of intersection with the periphery of the wheel, thereby reenforcing the peripheral zone of the wheel when it is rotated in one direction—a clockwise direction as shown 60 in Fig. 2—and causing the same to present a hard work engaging surface, and when the wheel is rotated in a reverse direction presenting a relatively softer work engaging surface.

In this construction, as in that illustrated in Fig. 1, the series of parallel lines of adhesive uniting successive adjacent layers may be arranged at right angles to each other, or in any other desired angular relation to each other.

Another form of buffing wheel embodying the invention is illustrated in Fig. 3 in which suc-

sive layers are united by curved narrow lines of adhesive 16 extending from the center to the periphery of the wheel and diverging from each other from the center to the periphery. The lines of adhesive uniting adjacent layers may be so 5 constructed as to register either with each other or to be in offset or intermediate relation to each other.

Another embodiment of the invention is illustrated in Fig. 4 in which radial lines of adhesive 10 17 unite one pair of adjacent layers and intermediate radial lines of adhesive 18 unite the next adjacent layer thereto and so on throughout the thickness of the wheel.

Various other arrangements of lines of adhesive 15 uniting adjacent layers to each other may be employed, as will be readily understood by those skilled in the art. The width of the lines of adhesive, which unite the layers, relatively to the spaces therebetween may be in any desired 20 proportion dependent upon the desired flexibility or rigidity of the buffing wheel. It will thus be seen that a buffing wheel embodying the invention may be so constructed as to be adapted to any kind of work. 25

Buffing wheels embodying the invention present a more uniform buffing periphery throughout the life of the wheel than those in which the layers of buffing material are stitched together. Objectionable fraying of the wheel is avoided. 30 The buffing material contained in the peripheral pockets of buffing wheels, such as illustrated in Fig. 1, is more evenly distributed than is possible in the through and through stitched buffing wheel, and the efficiency of the wheel therefore is 35 greatly increased.

It will be understood that the particular embodiments of the invention shown and described herein are of an illustrative character and that various changes in form, construction and arrangement of parts may be made within the spirit and scope of the following claims. 40

Having thus described the invention, what is claimed as new, and desired to be secured by Letters Patent, is:

1. A buffing wheel comprising a plurality of 45 contacting layers of fibrous buffing material firmly united at predetermined spaced intervals by a tenacious adhesive.

2. A buffing wheel comprising a plurality of 50 contacting layers of fibrous buffing material, the adjacent layers of which are firmly united by spaced-apart lines of tenacious adhesive.

3. A buffing wheel comprising a plurality of 55 contacting layers of cloth, the adjacent layers of which are united by narrow lines of tenacious adhesive, the lines of adhesive uniting successive adjacent layers extending in diverging directions.

4. A buffing wheel comprising a plurality of 60 contacting layers of cloth, the adjacent layers of which are united by lines of tenacious adhesive, the lines of adhesive uniting successive adjacent layers being out of registry with one another.

5. A buffing wheel comprising a plurality of 65 contacting layers of cloth, the adjacent layers of which are united by parallel narrow lines of tenacious adhesive.

6. A buffing wheel comprising a plurality of 70 contacting layers of cloth, the adjacent layers of which are united by parallel sinuous narrow lines of adhesive extending entirely across the wheel, the greater majority of said lines of adhesive having curved end portions extending in similar angular relation to radii from their points 75

- of intersection with the periphery of the wheel, thereby reenforcing the peripheral zone of the wheel when it is rotated in one direction and causing the same to present a relatively hard 5 working surface and when the wheel is rotated in the reverse direction to present a softer working surface.
7. A buffering wheel comprising a plurality of contacting layers of fibrous material, the adjacent layers of which are united by intersecting narrow lines of tenacious adhesive so distributed over the working area thereof as to form circular 10 series of pockets successively opening to the periphery as the wheel wears away.
15. 8. A buffering wheel comprising a plurality of contacting layers of cloth, the adjacent layers of which are united by series of parallel narrow lines of tenacious adhesive so distributed over the working area thereof as to form peripheral 20 open pockets surrounding closed pockets which successively open to the periphery as the wheel wears away.
9. A buffering wheel comprising a plurality of contacting layers of cloth so arranged that the 25 warp and woof of one layer extend in different directions to the warp and woof of the adjacent layer, the adjacent layers being united by parallel narrow lines of tenacious adhesive spaced apart at intervals relatively wider than the lines 30 of adhesive.
10. A buffering wheel comprising a plurality of contacting layers of cloth so arranged that the warp and woof of one layer extend in different directions to the warp and woof of the adjacent 35 layer, the adjacent layers being united by a plu-
- rality of series of parallel lines of adhesive uniformly spaced apart, each series of lines of adhesive intersecting those of another series to form pockets successively opening to the periphery as the wheel wears away.
11. A buffering wheel comprising a plurality of contacting layers of cloth, the adjacent layers of which are united by intersecting narrow lines of tenacious adhesive so distributed over the working area thereof as to form pockets successively 10 opening to the periphery as the wheel wears away, the intersecting lines of adhesive uniting two adjacent layers being so positioned relatively to the lines of adhesive uniting the next adjacent layer thereto that the pockets between adjacent 15 layers are in staggered relation to each other.
12. A buffering wheel comprising a plurality of contacting layers of cloth, the adjacent layers of which are united by intersecting series of 20 parallel narrow lines of tenacious adhesive so distributed over the working area thereof as to form pockets successively opening to the periphery as the wheel wears away, the respective intersecting lines of adhesive uniting two adjacent 25 layers being so positioned relatively to the respective series of parallel intersecting lines of adhesive uniting the next adjacent layer thereto that the pockets between successive adjacent layers are in staggered relation to each other. 30
13. A buffering wheel comprising a plurality of contacting layers of fibrous buffering material, the adjacent layers of which are firmly united by spaced-apart narrow lines of latex composition.
